UNITED STATES PATENT OFFICE.

JOSEPH R. CRAIG, OF LOUDONVILLE, OHIO.

DESIGN FOR A BODY FOR A BABY-CARRIAGE.

58,549.

Specification for Design.

Patented Aug. 2, 1921.

Application filed May 2, 1921. Serial No. 466,237. Term of patent 14 years.

To all whom it may concern:

Be it known that I, JOSEPH CRAIG, a citizen of the United States, residing at Loudonville, in the county of Ashland and State of Ohio, have invented a new, original, and ornamental Design for Bodies for Baby-Carriages, of which the following is a specification, reference being had to the accompanying drawing, forming part thereof.

Figure 1 is a side elevation of a body for baby carriage, showing my new design.

Fig. 2 is an end elevation thereof.

I claim:

The ornamental design for a body for a baby carriage, as shown.

JOSEPH R. CRAIG.
